TOGGLE SWITCH

Filed Sept. 11, 1931

UNITED STATES PATENT OFFICE

HUGH W. BATCHELLER, OF WORCESTER, MASSACHUSETTS

TOGGLE SWITCH

Application filed September 11, 1931. Serial No. 562,232.

This invention relates to an electric switch comprising a casing, circuit terminals insulated from each other and separated by a gap, and a hand piece lever movably connected with the casing and carrying a conductor which is movable by the lever to an "on" position bridging the gap between the terminals, and to an "off" position contacting with only one of the terminals.

10 The object of the invention is to produce a very simple and inexpensive switch having few parts adapted to be quickly assembled to form an efficient and durable switch.

Of the accompanying drawing forming a part of this specification,—

Figure 1 is a front view of a switch embodying the invention.

Figure 2 is a rear view.

Figure 3 is an edge view.

20 Figure 4 is a section on line 4—4 of Figure 2.

Figure 5 is a section on line 5—5 of Figure 2, showing the "on" adjustment of the switch.

25 Figure 6 is an enlargement of a portion of Figure 5, showing the "off" adjustment.

Figure 7 is a perspective view of the hand piece lever.

Figures 8 and 9 are perspective views of 30 the terminals.

Figure 10 is a rear view of a differently formed switch embodying the invention.

Figure 11 is an edge view partly in section of the switch shown by Figure 10.

35 Figure 12 is a section on line 12—12 of Figure 10.

The same reference characters indicate the same parts in all of the figures.

The casing portion of the switch shown by 40 Figures 1 to 6, inclusive, is composed of two members, viz: a sheet metal front member including a central facing 12 having a lever-receiving orifice 17, and insulator attaching means projecting inwardly from said facing, 45 and a one-piece insulating member or insulator 13 engaged with said attaching means and spaced thereby from the facing 12.

The attaching means is preferably integral with the facing, and in this instance is embodied in ears 14 bent inward from the oppo-

site edges of the facing, and seated on the insulator, and spacing the latter from the facing, and prongs 15 integral with the ears 14 and inserted in slots in the insulator and clinched on the inner side thereof. The casing may be attached to a wall or other support by integral extensions or ears 16, on the facing 12.

55 The facing 12 and the insulator attaching means when integral with each other may be made in one piece which is so formed that it may be stamped from sheet metal, and is adapted to engage a one-piece insulator.

The insulator is provided with an orifice 18 aligned with the orifice 17 in the facing 12, 60 and is also provided with terminals 24 and 25 insulated from each other and attached to the insulator by screws 26. The terminals are separated by a gap within the orifice 18. The terminal 24 has an end portion 24a projecting into the orifice 18, and the terminal 25 has a resilient end portion 25a also projecting into said orifice, each terminal having prongs 28 inserted in the insulator and clinched on the inner side thereof. 70

75 The facing orifice 18 is angular and preferably square, as best shown by Figure 1.

19 designates a preferably one-piece switch lever of insulating material such as bakelite. Said lever extends through, and is oscillatable in the orifice 18 and has an angular cross section conforming to the angular margin of said orifice, so that the lever is prevented from turning on its longitudinal axis in said orifice, and therefore can oscillate only in a 80 predetermined path.

The lever 19 is provided with preferably integral fulcrum studs 20 projecting from two of its opposite sides, and in rocking contact with the inner side of the facing 12. 90 Said projections are so arranged that the lever has a longer outer arm and a shorter inner arm, as best shown by Figure 7. The lever has a longitudinal guiding recess 22 extending through the shorter arm and into the longer arm, the fulcrum studs 20 being wholly on the exterior of the lever so that the recess extends between said studs into the longer arm.

95 A gap bridging conductor 21, preferably a 100

metal ball, is movable in the recess 22. An elongated helical spring 23 is seated on the inner end of the guiding recess and presses the conductor against both of the terminals 24 and 25 to close the gap when the lever is in the position shown by Figure 5, and against the terminal 25 to leave the gap open when the lever is in the position shown by Figure 6.

The described elongation of the guiding orifice 22 permits a corresponding elongation of the spring 23, so that the spring reacts on the inner end of said guiding orifice when the conductor bears on either, or both of the terminals, with sufficient force to hold the fulcrum studs 20 firmly against the inner side of the facing 12, and thereby prevent any possibility of loose movement of the lever.

The casing portion of the switch shown by Figs. 10, 11 and 12 is also composed of two members, one being a preferably one-piece sheet metal member, and the other a one-piece insulator. Said casing portion is adapted to be detachably secured to a support such as the dash of an automobile, and used, for example, for controlling a circuit which operates a dome light or a cigar lighter.

In this embodiment of the invention the insulator attaching means is preferably integral with the facing (here designated by 120), and is embodied in a base preferably integral with and surrounding said facing.

Said base includes a marginal portion 121 having a flat inner side on which the insulator 130 bears, as shown by Figure 12, a rim portion 123 bearing on the margin of the insulator, and ears or prongs 124 on the rim portion bent inwardly upon the outer side of the insulator.

An annular portion 122 of the sheet metal 40 of which the facing and base are formed, offsets the base portion 121 from the facing 120.

The base portion 121 is provided with an extension 121a (Fig. 11) projecting above the insulator and constituting a fixed clamping jaw adapted to bear on one side of the support *a*, and adapted also to support the bracket next described.

Said bracket includes an inner end member 127 bearing on the extension 121a and held against the latter by the rim portion 123, and ears 128 (Figs. 10 and 11) formed thereon and bent over the outer side of said bracket member. An arm portion 126 of the bracket member projects as shown by Figure 11, and has an ear 129 at its outer end containing a tapped orifice. A clamping screw 125 is engaged with the ear, and is adapted to bear on the opposite side of the support *a*, said screw constituting another clamping jaw.

Downward displacement of the bracket from the position shown by Figures 10 and 11 is prevented by two of the ears 124, the

under side of the arm member 126 bearing on said ears.

The last described embodiment is provided with the terminals 24 and 25, the switch lever 19, the conductor 21, and the spring 23, all arranged to function as already described, the facing 120 having an angular orifice 17a and the insulator an orifice 18a, these functioning like the orifices 17 and 18.

I claim:

1. A toggle switch comprising a sheet metal facing having an angular lever-receiving orifice and insulator attaching means projecting from the inner side of the facing; an insulator engaged with said attaching means and spaced thereby from the facing, said insulator having an orifice aligned with the facing orifice; terminals attached to the insulator and separated from each other by a gap adjacent the insulator orifice, a one-piece switch lever extending through and oscillatable in the facing plate orifice and having an angular cross section conforming to the angular margin of said orifice, whereby the lever is prevented from turning on its longitudinal axis in said orifice, said lever having fulcrum studs projecting from two of its opposite sides and in rocking contact with the inner side of the facing, said projections being so arranged that the lever has a longer outer arm and a shorter inner arm, the lever having a longitudinal guiding recess extending through the shorter arm between said fulcrum studs and into the longer arm, a gap-bridging conductor movable in said recess, and an elongated helical spring seated on the inner end of said guiding recess and pressing the conductor against the terminals, and the fulcrum studs against the inner side of the facing, the lever being movable to cause the conductor to close and open the gap between the terminals.

2. A toggle switch as specified by claim 1, said facing and insulator attaching means being made in one piece from sheet metal.

3. A toggle switch as specified by claim 1, said lever and its fulcrum studs being made in one piece from insulating material.

4. A toggle switch as specified by claim 1, said insulator attaching means including a clamping jaw portion having means for securing a bracket member thereto.

In testimony whereof I have affixed my signature.

HUGH W. BATCHELLER.
